POWER UNIT FOR A FOOD MIXER

Dave Chapman and Robert C. Le Sueur, Chicago, Ill.,
assignors to Scovill Manufacturing Company, Water-
bury, Conn., a corporation of Connecticut

Filed Oct. 19, 1964, Ser. No. 82,230

Term of patent 14 years

(Cl. D44—1)

Fig. 1

Fig. 2

FIG. 3

FIG. 4

FIG. 5

FIG. 6

FIG. 1 is a perspective view of a power unit for a food mixer, showing our new design;
 FIG. 2 is a side elevational view;
 FIG. 3 is a top plan view;
 FIG. 4 is a front end elevational view;
 FIG. 5 is a rear end elevational view; and
 FIG. 6 is a bottom view thereof.

We claim:

The ornamental design for a power unit for a food mixer, as shown.
